(57) **CLAIM**

The ornamental design for a reagent bottle, as shown and described.

DESCRIPTION

FIG. 1 is a front elevation view of a reagent bottle with the cap on showing our new design;

FIG. 2 is a rear elevation view thereof;

FIG. 3 is a left side elevation view thereof;

FIG. 4 is a right side elevation view thereof;

FIG. 5 is a top plan view thereof;

FIG. 6 is a bottom plan view thereof;

FIG. 7 is a first perspective view thereof;

FIG. 8 is a second perspective view thereof;

FIG. 9 is a front elevation view of the reagent bottle with the cap removed;

FIG. 10 is a rear elevation view thereof;

FIG. 11 is a left side elevation view thereof;

FIG. 12 is a right side elevation view thereof;

FIG. 13 is a top plan view thereof;

FIG. 14 is a bottom plan view thereof;

FIG. 15 is a first perspective view thereof; and,

FIG. 16 is a second perspective view thereof.

The broken lines depict portions of the reagent bottle that form no part of the claimed design.

1 Claim, 16 Drawing Sheets
